UNITED STATES PATENT OFFICE.

THEODORE H. GOTISAR, OF SOUTH ORANGE, NEW JERSEY.

TRAVELING BAG.

Application filed April 30, 1926. Serial No. 105,669.

This invention relates, generally, to improvements in traveling bags; and the invention has reference, more particularly, to a novel construction of traveling bag, 5 satchel, hand-bag or similar article, in which the body of the bag comprises two stiffened side-members, portions of which are turned toward each other and secured together to form the bag ends, each side 10 member being cut away intermediate lower and upper sections thereof so as to provide open portions forming longitudinally extending slits or gaps, in which slits or gaps are inserted and secured, by stitching or 15 otherwise, relatively soft flexible members or gussets, extending longitudinally through the side portions of the bag body, so that the upper stiffened sections of said sides are adapted to be readily collapsed relative to 20 the lower stiffened sections, to thereby permit a full width opening of the bag.

The present invention, therefore, has for its principal object to provide a strong, neat and sightly bag, so constructed that the relatively soft flexible members of the sides by collapsing permit the upper stiffened sections of the bag sides to open the full width and length of the bag body, and also to be self-retained against accidental closing, thus 30 providing increased and easily accessible packing space.

Other objects of the present invention not at this time more particularly enumerated will be more fully understood from the following detailed description of the present invention.

With the various objects of the present invention in view, the said invention consists, primarily, in the novel collapsible bag hereinafter set forth; and, the said invention consists, furthermore, in the novel arrangements and combinations of the various devices and parts, as well as in the details of the construction of the said parts, all of 40 which will be more fully described in the following specification, and then finally embodied in the clauses of the claim, which are appended to and which form an essential 45 part of the said specification.

50 The invention is illustrated in the accompanying drawings, in which:

Figure 1 is a perspective view of a bag made according to and embodying the principles of the present invention, the bag being 55 shown closed; and Figure 2 is a similar view, showing the bag opened.

Figure 3 is a transverse vertical section of the bag, said section being taken in Figure 1; and Figure 4 is a similar section of the bag, said section being taken in Figure 2. 60

Figure 5 is a blank of one of the side-members of the bag-body; Figure 6 is a detail sectional representation of a portion of said blank, said section being taken on line 6-6 in said Figure 5, and showing in perspective the opened-out slotted end-portion of the blank; and Figure 7 is a perspective view of a flexible member or gusset used with the blank illustrated in said Figure 5. 65

Similar characters of reference are employed in all of the said above described views, to indicate corresponding parts. 70

Referring now to the several figures of the drawings, the reference-character 1 indicates a complete bag showing one embodiment of the principles of the present invention, the same comprising a suitable bottom 2 of suitable marginal configuration, said bottom being usually made of leather, and being provided upon its inner face with a 80 reinforcing or stiffening member 3, of cardboard, fiber, or any other suitable material. The body of the bag consists of a pair of suitably formed body-members, as 4, of leather or other suitable material, said members being suitably formed so as to provide sides 5 and ends 6, substantially as shown in Figures 1 and 2 of the drawings. 85

As indicated in Figure 5, the members 4 are longitudinally slotted, as at 7, and at the ends of the slits 7 are cross-cuts 8. Above the slit 7 of each member 4, and connected with the lower sections or parts thereof, as at 9 and 10, are the upper mouth-forming sections or members 11, provided along their 95 marginal edges 12 with a closing means 13, such as a "Zip" closure, or, if desired, with an ordinary suitably constructed frame-structure. The said section or members 11 are also provided with suitably formed handles, as 14. Prior to bending or forming the members 4 into the shape shown in Figures 1 and 2, the lower marginal edge-portion of each member 4 is inwardly bent, as at 15, and the portions bounding the slits 7 are also inwardly bent, as at 16 and 17, so as to provide a longitudinally extending opening 18. These openings 18 when the parts of the bag assume the positions indicated in Figure 1 of the drawings, open up 100 as shown. Secured to the margins of said openings 18 so as to be inserted in the lat-

105

110

ter as parts of the bag body intermediate the upper and lower sections of the bag sides are relatively soft flexible members or gussets 19. As shown in Figures 3 and 4, the 5 lower and upper section of the body members 4 are respectively re-enforced or stiffened by card-board members 20 of substantially the same shape as the body members 4. At the joints, between the inwardly bent 10 portions 16 and 17 and the flexible members or gussets 19, I have suitably arranged welts, as 21, the parts being secured together by stitching 22, which also holds in place inner linings, as 23 and 24 of any suitable 15 material. The lining 23 may also extend over the inner portion of the bag, the parts being suitably secured together by stitching 25, or other suitable securing means.

Having, in the foregoing, described the 20 general arrangement of the several elements comprising my novel bag, the operations of closing and opening the bag will be fully understood from an inspection of the several figures of the drawings.

25 In opening the mouth of the bag, the upper stiffened sections or members 11 of the bag sides swing outwardly and downwardly toward the lower sections 4, the longitudinally extending flexible members or gussets 19 tending to collapse laterally, to thus permit the parts to assume the relative positions indicated in Figs. 2 and 4, and so that said upper sections or members 11 will be swung into or even beyond the vertical 30 plane of the lower sections 4, whereby the full width opening of the bag is attained.

I have thus devised a strong bag that 40 opens full width all the way across from side to side thereof, thus offering no obstruction to the insertion of articles within the bag interior. Such full opened condition of the bag is self-maintained by gravity acting upon the upper sections, and consequently the bag may be readily filled up to 45 its fullest capacity. My invention also provides a bag structure of neat and sightly appearance, which may be made in various sizes to serve as a traveling bag, hand bag, vanity bag, pocket-book, or any other desired specific type or kind of bag.

I am fully aware that some changes may 55 be made in the general arrangements and combinations of the various devices and parts, as well as in the details of the construction of the said parts, without departing from the scope of the present invention, as set forth in the foregoing specification, and as defined in the clauses of the claim which are appended thereto. Hence, I do 60 not limit my present invention to the exact arrangements and combination of the various devices and parts, as described in the said specification, nor do I confine myself

to the exact details of the construction of the said parts, as illustrated in the accompanying drawings. 65

I claim:—

1. A bag comprising relatively stiff bottom and combined end and side members, each combined end and side member being 70 longitudinally slitted so as to form a lower portion and an upper mouth-providing portion, said lower and upper portions being connected at the ends of the slit, said combined end and side members being adapted 75 to be opened up along their slits to provide gusset receiving openings, and relatively flexible gusset members inserted and secured within said openings between said lower and upper portions of said combined end and 80 side members.

2. A bag comprising a bottom and two side members suitably reinforced with stiffening material, portions co-extensive with the ends of said side members being turned 85 toward each other and secured together to form bag ends, each side member being longitudinally subdivided to provide a stationary lower section and an upper section 90 movable laterally relative to said lower section, a relatively soft flexible gusset member inserted and secured between the lower and upper section of each side member, and said gusset members being adapted to yield to the lateral movements of said upper sections whereby the latter may be swung outwardly substantially into the vertical planes 95 of said lower sections to unobstructedly open the bag interior to the full extent of its width and length. 100

3. A bag comprising a bottom and two side members suitably reinforced with stiffening material, portions co-extensive with the ends of said side members being turned toward each other and secured together to 105 form bag ends, each side member being longitudinally subdivided to provide a stationary lower section and an upper section movable laterally relative to said lower section, a relatively soft flexible gusset member inserted and secured between the lower and upper section of each side member, said gusset members being adapted to yield to the lateral movements of said upper sections whereby the latter may be swung outwardly substantially into the vertical planes 110 of said lower sections to unobstructedly open the bag interior to the full extent of its width and length, and means for separably securing together the free meeting 115 edges of said upper sections of said bag sides to close the bag. 120

In testimony, that I claim the invention set forth above I have hereunto set my hand this 27th day of April, 1926.

THEODORE H. GOTISAR.
